(57) **CLAIM**

The ornamental design for a vehicle walkway cover, as shown and described.

DESCRIPTION

FIG. 1 is a perspective view of a vehicle walkway cover depicting our new design;

FIG. 2 is a top plan view thereof;

FIG. 3 is a bottom plan view thereof;

FIG. 4 is an end view thereof;

FIG. 5 is an opposite end view thereof;

FIG. 6 is a view of a first side thereof;

FIG. 7 is a view of a second side thereof; and,

FIG. 8 is a perspective view depicting a bottom surface thereof.

The broken lines shown in the drawings are for the purpose of illustrating portions of the article that form no part of the claimed design.
